UNITED STATES PATENT OFFICE.

HARRY G. DYER, OF GLOUCESTER, NEW JERSEY.

ELECTRIC INDICATOR FOR TRAINS.

No. 861,715.

Specification of Letters, Patent.

Patented July 30, 1907.

Application filed February 11, 1907. Serial No. 356,799.

To all whom it may concern:

Be it known that I, HARRY G. DYER, a citizen of the United States, residing in the city of Gloucester, county of Camden, State of New Jersey, have invented a new and useful Electric Indicator for Trains, of which the following is a specification.

Figure 1 represents a rear view of a locomotive cab and section of rails and contact strips embodying my invention. Fig. 2 represents in top plan view, a signal 10 track equipped with the side conducting signal rails in accordance with my invention. Fig. 3 represents, on an enlarged scale, a portion of Fig. 1. Fig. 4 represents in diagrammatic form, the connections in the locomotive. Fig. 5 represents in top plan view, a draw- 15 bridge connection embodying my invention. Fig. 6 represents the draw-bridge protective contact in longitudinal section with diagrammatic view of the connections thereof. Fig. 7 represents a sectional view of a whistle and its connections.

20 Similar numerals of reference indicate corresponding parts in the figures.

Referring to the drawings:—1 designates a locomotive shown in dotted lines herein, to clear from the other parts of the invention, said locomotive being 25 provided with an engine 2 and dynamo 3 for generating the signaling current independently of the movement of the locomotive. It will be evident that this need be of but small size and may be of any convenient or desired type.

30 At a suitable point as to be within the sight of the engineer, are the signal box 4 and whistle 5, which will be more fully described hereinafter.

The signaling is accomplished by means of side signal rail connections located in proximity to the track 35 and which I have represented as three in number, 6, 7, and 8, arranged in sections with a brake between the sections. The section 7 at one point is connected to the section 6 of the preceding set of sections and this cross connection is continued from point to point with 40 the effect that the shoe of one train or locomotive pressing upon the conductor 7 will be longitudinally connected with the shoe of the following locomotive or train pressing upon conductor 6, at all times when these two trains are upon adjoining sections of signaling 45 conductor.

The conductor rails 6, 7 and 8 are preferably supported by means of a standard 9 to which for convenience I connect an overhang 10, protecting the same from mechanical injury and electrical interference. 50 I mount the rails within this connection by means of a bolt 11, having a lateral turned end 12 or other lateral connection by which tightening of the nut 13 upon the bolt will hold the insulator 14 securely against the support 9. The insulator 14 is preferably provided with 55 a substantially flat interior surface and with angular

edges 15 and 16 at the two extremities thereof, said angular edges conforming to the shape of the corresponding face of the conductor 6 or 8 which is intended to come in contact therewith. At an intermediate point, in the case of three conductors to be supported 60 at two points intermediate, I provide wedge shaped insulators 17 and 18 held in place by any suitable means as by bolts 19 and 20. The larger portions of the insulators are outwardly directed with reference to the surface of the insulator 14 with the result that 65 plurality, in this case three, dove-tailed grooves are provided which support and retain the rails 6, 7 and 8 respectively.

It will be evident that with variant cross sections of rails different corresponding shapes of insulator adjoining the same may be necessary or desirable to properly support and insulate the rails. Contact with these downwardly directed rails is made by means of shoes 21, 22 and 23 which are correspondingly upwardly directed to make contact with the rails. These shoes or 75 collectors are insulated at 24 from a supporting arm 25, which I have illustrated as comprising direct support for the shoes and insulators thereof and an upwardly extending portion 26 supporting the same over the floor of the engine cab. It will be evident that the shape 80 of this support is immaterial, its function being to properly hold the shoes in contact with the conductor rails, supporting them upon any fixed part of the train. The arm 25 may be of spring material or springs of any suitable character may be made use of to support the 85 shoes, which is well known in the art.

I preferably provide a plurality of signaling devices which are illustrated diagrammatically along with the connections thereof in Fig. 4 and I will now describe the normal connections for track signaling devices as 90 shown in Fig. 4. A storage battery 27 is connected in such a way as to be thrown across the terminals of the dynamo 3 when desired for charging purposes or to be connected directly to the conductor 28, by which connection is made from said dynamo 3 to the shoe 22 to 95 bear against contact rail 7. The conductor 29 connects from the other dynamo terminal and one battery pole to the car truck, returning the current through the wheel 30 and track. The shoe 21 is connected to conductor 31 with an annunciator winding 34, the annunciator of which is arranged at one of the openings as 33 in the annunciator 4. At the opening, as 32, in said annunciator frame, I provide a lamp 35 which is in parallel with the winding of the annunciator 34 and at any suitable point I arrange my electrical whistle, whose 100 windings 36 are also connected in parallel with the annunciator drop and lamp. The conductor is ultimately connected also to the frame of the engine and I have shown it as connected to the wheel 30. I have shown these conductors 31 and 29 as connected to the wheel 110

and it will be evident that the connections of each through the frame are similar in this regard and that the conductor 29 of one train is in electrical connection with the conductor 31 of each preceding train as well as 5 each following train through the medium of the track rail 37 at all times.

In operation the generator 3 of one locomotive or train for the battery when it is desired to work upon the storage battery, is connected at one terminal to the 10 track rail and at the other terminal to the shoe 22 by which current is impressed upon the signaling rail 7 of the section or track upon which this engine or train is operating. The connection is thus formed with the conductor 6 of the preceding section and a following 15 train will form electrical contact therefor with this side of the dynamo of the other train through the shoe 21 and the contact will be completed through the signals 32, 35 and 36 in parallel and the rail 37. Thus every 20 train upon one section of track will be directly signaling any train upon the next section as soon as this following train enters the section. It will also be evident that the sections may be made of any necessary or desired length and that the length may be varied from 25 point to point throughout the system according to the congestion of traffic or other conditions.

In order that the engineer may check the transmission of current to the contact rail 22 insuring contact of the shoe, and the maintenance of the rail in place or warning of the contrary, I provide an additional contact 38 which may be supported upon the arm 25 just 30 behind the shoe 22 but electrically insulated therefrom. This collector 38 is connected by means of conductor 39 with the car wheel 30 through a lamp or other suitable signal 40 which may be placed at any 35 other suitable opening 41 in my annunciator frame. During the normal operation of my system the lamp 40 should be continuously lighted and any failure to so light the lamp 40 would give immediate notice to the engineer of trouble in the system.

40 In order to protect against open switches and draw-bridges and give warning thereof to the engineer of an approaching train, I provide a construction typified by Fig. 6 and which I have illustrated as connected with the draw-bridge of Fig. 5. In this construction 45 I make use of the outer collector shoe 23 and the conductor 8 arranged to engage an abutment 42 when in closed position. Upon the abutment 42 I arrange a switch 43 having a projecting operating rod 44 to be moved by the edge 45 of the draw in its final movement 50 into place. In the form which I have illustrated this switch is made up of a casing or frame 46 separable for convenience of manufacture and provided with support as at 47 and 48 for the movable rod 44, said rod, being normally maintained in the position shown in 55 Fig. 6 by any suitable means, as by a spring. Upon the center of this rod and in electrical contact therewith, I form an enlargement preferably in the form of a disk 50 and in proximity to said enlargement, I place insulation 51, 52 even with the surface of said enlargement 60 in order that the cooperating contact 53 may ride freely and without appreciable vertical movement upon either the enlargement or the insulation according to the position of the rod 44. The contact 53 is in the form of an arm preferably pivoted at 54 and held at 65 its duty by a spring 55. The arm is insulated from the

frame of my casing by insulation 56 and a binding post 57 is electrically connected to said arm and is insulated from the frame as at 58. The binding post 59 is in electrical contact with the rod 44 and enlargement 50. The binding post 59 is connected by means of conductor 60 with the track rail 37, which as has already been described, is connected by means of conductor 29 in the train with one side of the dynamo of each engine or train. The binding post 57 is connected by means of conductor 61 with the conductor 8 which is connected by means of shoe 23 and conductor 62 with the lamp 63, which may be arranged in any suitable opening 64 in the annunciator frame 4, the opposite side of the lamp 63 being connected by means of conductor 64 with the brush of the dynamo to which conductor 28 80 is connected, that is the brush opposite the one mentioned in contact with the wheel 30. It will thus be seen that at all times when the draw is open contact will be made by means of the enlargement or disk 50 with the contact 53 and through the shoe 23 and signaling conduction 8, the lamp 63 will be maintained in lighted condition in each train. This condition is maintained not only when the draw is entirely open but until the draw is as nearly closed as the required movement of the switch 50 contemplates the final act 85 of closing, breaking this connection and cutting off the current from the light, but any form of switch which will accomplish the result will be desirable.

For the purpose of protecting against open rail switches the same general form of construction may be 90 used, the switch which I have illustrated being thrown directly by movement of the point of the rail switch itself or by the final movement of the lever which accomplishes this rail movement. The connections by the open character of the switch are communicated to 100 the engineer could be made the same as those which I have illustrated and described for the draw-bridge.

The electric whistle of which I make use comprises a casing on top wrapped by a solenoid and inclosing a movable piston or magnetic material which will be 105 operated by the solenoid. At the top of the chamber formed I provide a passage 69 communicating with any usual or ordinary form of whistle 70. In order to prevent excessive movement of the piston in a downward direction I provide a stop 71. It will be evident that 110 passage of current through the solenoid 36 will cause movement of the piston within said chamber and consequent rush of air through the whistle operating the same.

Having thus described my invention, what I claim 115 as new and desire to secure by Letters Patent, is:—

1. In a device of the character described, a train, an engine and dynamo thereon, a track, a plurality of signal rails in proximity to said track and arranged in sections, electrical connections between rails in different relative position in different sections, shoes making contact with said signal rails only, a signal electric connection between one of said shoes and one side of the dynamo, and connection from the other side of said dynamo to another of said shoes.

2. In a device of the character described, a railway track, a plurality of signal rails arranged in sections adjacent thereto, a plurality of trains operative upon said track, an engine and dynamo upon each of said trains, shoes upon each train bearing upon each of said signal rails only, electric signals upon each of said trains, connections from the dynamo to each of said shoes including the electrical signal in one of said connections and means

for connecting signal rails of one section with a differently placed signal rail in adjoining section.

3. In a device of the character described, a train, a source of electric energy supported thereon, a plurality of signal rails supported in proximity to said train, a collector, shoes supported on said train connected with said rails, connections from the source of energy to said shoes including an electric signal, a shoe in line with one of said shoes to bear upon the same, signal rail and connections embodying an electric signal between said shoe and one side of said source of electric energy.

4. In a device of the character described, a track therefor, a source of electric energy grounded upon one side of said track, a signal rail in proximity to said track, a shoe connected with the other side of said source of electric energy and bearing upon said signal rail, an electric signal in said connections and a movable rail comprising one of said track rails, an electric switch connected on one side to the track rail and upon the other side 20 to the signaling rail and to the source of energy on the train and means whereby the movable rail throws said switch only in its final movement into place.

5. In a device of the character described, a solenoidal winding, a closed core operating as a piston therein and a 25 whistle communicating with the interior of the cylinder.

6. In a device of the character described, a solenoid, means for substantially closing one end thereof, a solenoidal core normally lying at the opposite end of the solenoid and operating as a piston therein and a whistle con-

nected with the solenoid by an aperture in the practically closed end.

7. In a device of the character described, an electric switch, a fixed casing, a plunger operatively supported in the opposite ends of said casing, insulating material on said plunger, a contact level with said insulating material, 35 an electric connection with said casing, insulation supported upon the interior of said casing, a pivotally mounted contact plunger supported on said insulation, a spring exerting its influence at right angles to the movement of said first named plunger normally holding said contact 40 plunger against the insulation and electric connections with said contact plunger.

8. In a device of the character described, an electric switch, a fixed casing, a plunger operatively supported in the opposite ends of said casing for sliding movement therein, insulating material on said plunger, a contact level with said insulating material, an electric connection with said casing, insulation supported upon the interior of said casing, a pivotally mounted contact plunger supported on said insulation, a spring normally holding said contact 45 plunger against the insulation, electric connections with said contact plunger and a spring adapted to hold the plunger in position with its contact piece against the contact plunger.
